Hos'g Sprague

United States Patent Office.

DAVID VOGT, OF TRENTON, MICHIGAN.

Letters Patent No. 102,889, dated May 10, 1870.

IMPROVED HARNESS-BUCKLE.

The Schedule referred to in these Letters Patent and making part of the same.

To whom it may concern:

Be it known that I, DAVID VOGT, of Trenton, in the county of Wayne, and State of Michigan, have invented a new and useful Improvement in Harness-Buckles; and I do declare that the following is a true and accurate description thereof, reference being had to the accompanying drawings and to the letters of reference marked thereon, and being a part of this specification, in which—

Figure 1 is a plan of the body of the buckle;

Figure 2 is a bottom plan of the buckle-plate;

Figure 3 is an elevation of the screw; and

Figure 4 is a perspective, showing the buckle connecting two straps.

Like letters indicate like parts in each figure.

The nature of the present invention relates to an improved construction of harness-buckles, and consists in so constructing the same that the draft-strain of the loose strap or tug will be equally divided between two studs projecting through it from the buckle, and a screw-bolt passing through a covering-plate, the strap and body of the buckle; also, in providing the covering-plate with a slide, which engages with a groove in the neck of the screw-bolt, and prevents the latter from working loose.

In the drawings—

A represents the body of my improved buckle, provided with two studs, *a*, in line with and equidistant from a central threaded opening, *b*. The buckle shown being designed to connect the hame-tug and trace, in addition to the loop *c*, at one end, by which the hame-tug is secured to it, is provided at the other end with a loop, *d*, to which the breech-strap is secured.

e are loops at the sides of the buckle, to which the back and belly-bands are attached.

B is a covering-plate, through which are two openings, *a'*, for the reception of the studs *a*.

b' is an opening through the plate, coincident with the opening *b* in the buckle.

On the under side of the plate a slide, *f*, is dovetailed therein at one side of the opening *b*, and is

moved back and forth by a small stud, projecting up through a slot in the plate.

C is a screw-bolt, whose threaded end screws into the central opening in the buckle, passing through the covering-plate and trace *D*.

In the neck of the bolt is a groove, *g*, into which the edge of the plate or slide *f* enters, the effect of which is to prevent the rotation of the bolt.

The loop *c* has a screw running through the ends of its lugs, and around which screw the loop of the hame-tug is made and stitched. If it be desired to remove the buckle, it may be easily done by taking out the screw, when the buckle is replaced in like manner, without ripping the loop of the hame-tug.

When the buckle is secured, as shown in fig. 4, it will be seen that the draft-strain of the trace is distributed equally between the studs *a* and bolt *C*, giving three points of resistance, and diminishing the liability of tearing the trace at the tongue-hole; while the slide *f* prevents the bolt from working loose.

By punching the holes in the trace at a distance apart corresponding with the space from the bolt to the studs, the length of trace is readily adjusted as circumstances require.

In ordinary buckles the loops *d* and *e* may be dispensed with.

What I claim as my invention, and desire to secure by Letters Patent, is—

1. The buckle *A*, and plate *B*, the former provided with studs *a*, and threaded openings *b*, and the latter with corresponding openings *a'*, *a'*, and *b'*, and secured together by the bolt *C*, in the manner and for the purpose set forth.

2. In harness-buckles, the slide *f* in the plate *B*, and the groove *g* in the bolt *C*, as and for the purpose set forth.

DAVID VOGT.
